TEXTILE ROLL ASSEMBLING AND
DISASSEMBLING APPARATUS

Robert R. Elliott, Sr., Pawtucket, R. I., assignor,
by mesne assignments, to Whitin Machine
Works, a corporation of Massachusetts

Application December 30, 1948, Serial No. 68,358

1 Claim. (Cl. 29—238)

1

This invention relates to a portable apparatus and to a method for assembling and disassembling lengthy sectional textile rolls, and especially has to do with that form of rolls which are known as fluted rolls used in the drawing mechanisms of such textile machines as roving frames and spinning frames. The present invention has particular application to the roll coupling organization disclosed and claimed in my copending application, Serial No. 763,589, filed July 25, 1947, now abandoned.

Textile rolls of this class customarily are arranged as the lower drawing rolls and as the back feed rolls in the drawing mechanisms of the aforementioned textile machines, in which instances they are positively driven, usually from one end, for rotation in open top bearings formed in a series of spaced roll stands which are fixedly mounted upon the usual roller beam at one or both sides of the machine. In the majority of cases, these rolls are small in diameter and they form parallel lines extending longitudinally for substantially the entire length of such machines; the length of the individual rolls of each line varying from ten to forty-eight feet, or longer, depending upon the length of the particular machine upon which they are installed. In making up each line of these long, slender rolls, the present practice is to connect end-to-end a number of relatively short roll sections to form a continuous and complete roll assembly. Each section of the short roll components of these lengthy rolls is formed throughout its length with a series of alternate cylindrical neck portions and enlarged longitudinally fluted strand engaging portions in which some of the cylindrical neck portions may be of greater or less diameter than the others to serve as the bearing surfaces or journals for these rolls in their respective bearing stands.

Various coupling devices have been proposed for uniting the adjoining roll sections end-to-end in rotation-transmitting relationship, one common practice being to provide one roll section on one end beyond the journal bearing with a square shank or tang of a size adapted to have a driving fit within a square socket formed in the opposing end of the next adjacent roll section. Another arrangement in current use is to provide in the opposing ends of two adjacent roll sections cylindrical holes drilled in axial alignment with each other and with the roll sections, and to press into these holes with an extremely tight-forced fit a cylindrical journal member which unites the roll sections to form an integral

2

roll assembly. Another textile roll coupling arrangement is that shown in my copending application, Serial No. 763,589, filed July 25, 1947, which is an improvement over the joint structures above described in that the opposing ends of adjacent roll sections are formed with precision square shanks or tangs in axial alignment with each other and with the roll sections and pressed into a precision broached square hole 10 extending axially through a sleeve-like coupling member which carries upon its exterior a fluted boss, the shanks being machined to make an extremely tight pressed fit with the sides of the square hole in the coupling and forced home there-in from opposite ends thereof.

Considerable pressure, naturally, is required to secure these tight-forced fits and assemble the parts. Where multiple sections of the rolls are assembled for the first time such as, for example, 20 during building of the textile machine, this is a comparatively simple matter because large, heavy presses can be used without special difficulty but such presses due to their size and weight obviously cannot be used in the field for joining sections of rolls "in situ" upon the textile machine when installations of such rolls are made thereon during erection or repair operations.

The present invention, therefore, has for one of its objects the provision of an improved roll assembling and disassembling apparatus which will be sufficiently powerful to force together tightly or to spread apart the interengaging forced-fitted coupling parts of adjacent roll sections and which, at the same time, will be small enough and light enough to be readily portable and moved about from machine to machine to be readily handled thereon by the fitter in making or separating roll joints.

Another object of the invention is to provide a portable apparatus including a hydraulic press 40 which shall be adapted to be applied to the usual metal angle roller beams or rails which support the roll stands in which are journaled the relatively long sectional textile rolls of the machine.

The present invention has for another of its aims to provide a demountable hydraulic apparatus which can be selectively positioned upon the longitudinal framework of the textile machine relative to any two adjacent roll stands and will be so arranged as to establish pressure-transmitting relationships with some of the necks and fluted portions of the roll sections associated with these roll stands to press together or force apart the joint structure of said roll sections by 50 means of hydraulic action applied thereto in a

manner to produce axial movement of one of the roll sections bodily relative to the adjoining roll section in an appropriate direction to effect either union or separation of such forced-fit joint structures of the type above described.

The nature of the invention will be readily understood from the following description, when read in connection with the accompanying drawings, and the novel features will be particularly pointed out in the appended claim.

In the drawings:

Fig. 1 is an exploded view of sufficient of the drawing roll joint structure of my copending application, Serial No. 763,589, above referred to, to illustrate the purpose of the apparatus of the present invention;

Fig. 2 is a plan view of a portable hydraulic apparatus embodying the present invention applied to the roller beam of a spinning frame for carrying out a roll assembling operation;

Fig. 3 is a sectional view taken substantially on the line 3—3 of Fig. 2 but on larger scale, showing a side elevation of the portable roll assembling and disassembling apparatus illustrated in Fig. 2, in which portions of one of the support brackets for the press is broken away to expose details of the mechanism, and with one of the roll clamping devices being shown in an opened position;

Fig. 4 is a front view of one of the adjustable platform brackets shown in Figs. 2 and 3 for supporting the portable hydraulic press during roll assembling and disassembling operations;

Fig. 5 is a plan view of one of the roll clamping devices shown in Fig. 2, and

Fig. 6 is a longitudinal sectional view of the roll clamping device shown in Fig. 3 shown in a closed position when gripping a roll section during use of the hydraulic apparatus of the present invention.

Referring to Fig. 1, this figure illustrates portions of two roll sections to be joined or separated, as the case may be, the joint structure of these rolls embodying the invention disclosed and claimed in my copending application, Serial No. 763,589 filed July 25, 1947. As illustrated, this joint arrangement comprises two roll sections 10 and 12 and an intermediate tubular or sleeve-like coupling member 13, the opposed ends of the roll sections 10 and 12 being provided with the square shank portions 14 and 15 respectively. The roll sections 10 and 12 are of small diameter and carry a series of alternate enlarged longitudinally strand engaging fluted bosses 16 and 16' respectively and reduced neck portions 17 and 17' respectively. The coupling sleeve 13 is provided intermediate its ends with an enlarged fluted strand engaged fluted boss 18 at either side of which are the reduced cylindrical end portions 20 and 21 respectively. Extending axially through the coupling member 13 as a broached hole or bore 22 into which is pressed tightly from each end the square shanks 14 and 15 on the roll sections 10 and 12 respectively.

Fig. 2 illustrates the portable roll assembling and disassembling apparatus of the present invention in its normal operating position applied to the roller beam of a conventional spinning frame and readied for carrying out a roll assembling operation. As illustrated, this roll assembling and disassembling apparatus comprises a portable hydraulic press mechanism "per se" and generally designated by the numeral 25, and a pair of vertically adjustable platform brackets 26 and 26' which are arranged for attachment

to the usual roller beam 27 of the spinning frame and to support the press 25 in one of several selected elevated positions above the roller beam 27, the purpose of these different vertically adjusted positions being more fully set forth in the subsequent pages of the present specification.

The brackets 26 and 26' are of identical construction so that the description of one will suffice for the other, the details of which will be described hereinafter, and they are adapted to be clamped individually to the roller beam 27 at longitudinally spaced locations therealong in convenient positions where they will provide a pair of rest members for supporting the press structure 25 during use. In Fig. 2 there is further shown two of the numerous roll stands 28 and 28' carried by the roller beam 27 and in which the complete long sectional rolls, after assembly, are installed for rotation on the spinning machine. The two roll sections to be joined are here shown detached and with the intermediate fluted coupling sleeve 13 previously pressed onto the square shank 15 of the roll section 12.

Considering now Fig. 3, the bracket 26 is shown as comprising an angle clamp 30 having a body portion 31, the upper part of which is provided with a transverse projection 32 adapted to seat firmly on the top face of the roller beam 27, when the clamp 30 is applied thereto with its body portion 31 in contact with the depending leg 33 of the beam. The lower part of the body portion 31 has an inwardly directed oblique foot 34 in which is mounted a clamp screw 35 which has screw-threaded engagement in a boss 36 at the outer end of the foot 34. The screw 35 is provided at its outer end with a hand knob 37 whereby the screw 35 may be rotated to bring its rounded inner end to bear against the filleted corner of the under surface of the roller beam 27 to tightly secure the stand 26 in its desired position to the roller beam.

To support the press structure 25 during use on the machine, the bracket 26 carries a horizontal platform 40 which is elevatable by means of an upright rod 41 affixed to the underside of the platform 40 and slidably fitted into a vertical tubular member 42 which is suitably affixed to the outer face of the body portion 31 of the clamp 30, the tubular member 42 constituting an upstanding standard when the clamp 30 is applied to the roller beam 27. When thus mounted, the platform 40 may be selectively positioned by being raised or lowered into any of various vertically adjusted positions "A," "B," or "C" (see Fig. 3), and secured by pin 43 in any of these positions with its top surface substantially coincident with a horizontal plane tangent with the bottom of the usual roll stand bearings 45, 46 and 47 respectively. Pin 43 is positionable selectively in any one of a series of transverse holes 48, 48' and 48" in the rod 41 and the pin 43 is arranged to be manually retractable axially of the tubular extension 50 on the standard 42 against the compression of the spring 51 housed within the tube 50. The holes 48 are spaced at such positions along the rod 41 whereby the top surface of the flat platform 40 in each of its vertically adjusted positions will lie in a horizontally extended position and will be substantially tangent to the bottom of the bearing recesses in the several roll stands 28 and 28' in which rotates the particular roll being assembled or separated. The pin 43 has secured at its outer end a knurled knob 53 whereby the pin 43 may be retracted by the operator from any of the holes 48, 48' or 48".

when it is desired to raise or lower the platform 40 after completion of the roll coupling or separating operations of a completed roll and preparatory to performing subsequent coupling or disassembling operations upon another line of long rolls which are to be journaled in the same roll stands. In use, the portable press 25 is transported bodily by the fitter to the roller beam 27 and laid in a bridging relationship upon the forward extensions of the flat platform members 40 of the stands 26 and 26', the top surfaces of the respective platform members being pre-set so as to lie in horizontal planes which are substantially coincident with the bottoms of the respective bearings 45 or 46 or 47, as the case may be, of a pair of spaced roll stands 28 and 28' in which the particular line of roll sections thus assembled or to be parted rotates.

Referring to Figs. 2 and 3, the hydraulic press organization 25 of the roll assembling and disassembling apparatus of the present invention consists of a portable hydraulic ram unit generally designated 55 and a pressure-transmitting mechanism comprising a rail structure 57 to which is fixed an abutment 58, and three roll clamping devices 59, 59' and 59'' of identical construction, the clamp 59 being fixed to the rail structure 57 and the clamp 59' being adjustably clamped at various positions along the rail structure to suit the neck spacing of the roll section to be held, the clamps 59 and 59' acting to secure in a fixed position one of the two sections of rolls to be joined or separated, viz., roll 10 in this instance. The roll clamp 59'' for gripping the second roll section 12 is slideable along the rail structure 57 and when impelled therealong by pressure from the ram unit 55 will force either square 14 or 16 into or out of the square hole of the coupling 13 depending upon whether the roll sections are being coupled or separated. As illustrated, the clamp 59'' is positioned between the abutment 58 and the stationary clamp 59 and movable along the rail structure 57 when pushed towards the clamp 59 or in the direction of the abutment 58 by the ram unit 55 when the latter is placed at either side of the fixed clamp 59 to force the roll sections 10 and 12 either together or spread them apart by pressure reaction between the clamp 59'' and either the abutment 58 or the fixed clamp 59.

The rail structure 57 comprises a pair of parallel support rods 61 and 62 for supporting the clamps 59, 59' and 59'' and are disposed above and extend longitudinally of the roller beam 27 when the apparatus is in use. The rods 61 and 62 are secured at one end in suitably spaced bores in the abutment member 58 and are held fixed therein by means of suitable pins 64 and 65 respectively. The abutment member 58 as thus arranged, forms a cross-tie connecting and supporting the parallel rods 61 and 62 of the rail structure 57 in spaced relation and, in addition, serves as a pressure plate when engaged by one end of the ram unit 55.

As shown in Figs. 2 and 6, the clamp 59 is fixedly secured by pins 66 and 67 to the rods 61 and 62 respectively, the clamp 59 being affixed to the rods at a position therealong approximately five-ninths of their overall length as measured from the pressure plate or fixed abutment 58. For example, in one press unit built and tested, the rods 61 and 62 were made approximately 36 inches long and the distance between the centers of stationary clamp 59 and the pressure plate 58 measured approximately twenty inches.

Referring now to the roll clamping devices 59, 59' and 59'', these comprise individual clamp units arranged as above mentioned upon the rail structure 57, the fixed clamp 59 being pinned to the rods 61 and 62 by pins 66 and 67, the second clamp 59' being arranged to be adjustably positioned in desired adjusted positions on the rods 61 and 62 and there secured by a clamp screw 68 suitably arranged on this clamp, and the third clamp 59'' being freely slideable on the rods 61 and 62 either towards or away from the fixed clamp 59 depending upon which side of the clamp 59'' the the ram unit 55 is placed for engaging and imparting the propelling force thereto to push the clamp 59''. Otherwise, the three clamps are of similar construction so that the description of one will suffice for the others. As illustrated in Figs. 3 and 6, it will be seen that these clamps have a generally rectangular block-like base member 70 formed at the lower portion of one end with a V-shaped roll-receiving opening 71 which forms the fixed or stationary jaw of the clamp. The opposite side faces of the block 70 proximate to the V-opening 71 are recessed inwardly as indicated at 72 to provide the flat sided shoulders 73 and 74 which engage behind and in pressure-transmitting relation with the end of a roll boss of the particular roll sections being held by the clamps during a roll assembling or disassembling operation, as indicated at "a" or at "b" in Fig. 2. In effect, the stationary jaw presents a V-shaped opening 71 bounded by a pair of vertically opposed plate-like projections formed by the recess 72 and the shoulders 73 and 74 and these projections are of narrower width than that of the end of the block in which they have been formed. The opposite side faces of the shoulders or projections 73 and 74 are flat and lie in parallel vertical planes. The opposing bottom and top faces of the projections 73 and 74 respectively defining the V-opening 71 also are flat surfaces and make preferably a 45° angle with a horizontal plane bisecting the V-opening 71, and thus bear a right angular relationship to each other.

The top of the block 70 is provided with a relatively deep groove 75 which extends longitudinally of the block across its entire top face, as illustrated in Figs. 5 and 6. Mounted within this groove is the shank member 76 of the movable jaw 77 having at its outer end an enlarged depending L-shaped flange 78 the length of which is such that it will lie opposite the mouth of the V-shaped opening 71 of the fixed jaw in all extended or retracted positions of the movable jaw 77 relative to the block 70. The shank 76 of the movable jaw 77 is confined within the groove 75 by means of a plate 80 which is suitably secured to the top of the block 70, as by screws 81, and positioned across the end of the groove 75 closest to the flange 78 of the movable jaw.

To retract or to expand the movable jaw 77 with respect to the V-opening 71 there is provided a screw threaded rod 83 one end of which has threading engagement within a threaded opening 84 at the inner end of the shank 76 and secured therein by a pin 85 extending transversely of the rod 83 and the shank 76. The intermediate portion of the rod 83 is positioned within the open section of the groove 75 while the forward end portion of the rod 83 passes through a suitable hole in a plate 86 terminating the forward end of the groove 75 and suitably secured to the block 70. The rod 83 has

bearing in the plate 86 while the outer screw threaded end portion of the rod extends forwardly beyond the plate 86 for a substantial distance and carries thereon a hand wheel 88 carrying a hub 89 which has threading engagement on the threaded outer end portion of the rod 83. A coiled spring 90 mounted upon the intermediate portion of the rod 83 and extending between the inner end of the movable jaw 77 and the inner end face of the plate 86 normally tends to urge the movable jaw 77 outwardly of the groove 75 and away from the V-opening 71 forming the fixed jaw to obtain an opened position of the jaws as depicted in Fig. 3 when the hand wheel 88 is manually turned in a direction to unscrew it. Turning of the hand wheel 88 in the opposite direction to thread it further onto the rod 83 will retract the movable jaw 77 and pull it towards the V-opening 71 to draw the roll neck into the V-opening 71 and establish clamping engagement with the roll neck, as depicted in Fig. 6, whereby the roll neck will be engaged behind one end of the fluted boss by the shoulders 73 and 74 of the fixed jaw and by the flange 78 of the movable jaw and the roll neck will be tightly held in the V-opening 71 by the flange 78 during a roll assembling or disassembling operation. When roll sections having fluted bosses of different diameters are to be assembled or disassembled, then if the boss diameter is greater than that of the rods 61 and 62 which support the clamps 59, 59' and 59'', the rail structure 57 will pivot about rod 61 on the platforms 40 of the brackets 26 and 26' as indicated in Fig. 6 and the jaw end of the blocks 70 also will lift due to blocks 70 of all clamps being drawn toward the roll necks of their respective roll members upon continued turning of the hand wheel 88 and further retractive movement of the movable jaw 77 after the flange 78 of each clamp has engaged the respective roll necks. This action follows since the roll bosses proximate to the clamps rest against an abutment member 92 fixed to the top of the platform 40 so that the entire rail structure, the press, and the roll clamps 59, 59' and 59'' will be drawn bodily towards the roll sections after the flange 78 engages the roll neck. The roll neck upon entering the V-opening 71 and in being seated and clamped against the projections 73 and 74 causes the block 70 to tilt upwardly. No tilting of the block 70 will occur when the fluted boss is of the same diameter or smaller than that of the rods 61 and 62, otherwise the same pulling action of the clamps towards the roll neck will take place.

The hydraulic ram unit 55 of the roll assembling and disassembling apparatus comprises a ram cylinder 100 which forms the base portion of the ram unit, and a piston or plunger 101 axially extensible from one end of the cylinder 100. The ram cylinder 100 is adapted to receive fluid under pressure from a flexible fluid transmitting conduit 102 coupled as at 103 to the cylinder 100 of the ram unit and communicates with the interior of the ram cylinder. The flexible conduit 102 at its opposite end, is coupled by a hydraulic fitting 104 to the outlet port of a pump unit 105. The hydraulic ram unit 55 and the pump unit 105 may be of any of the well known types of portable hydraulic equipment commercially available on the market, the detailed construction of which forms no part of the present invention. For example, the ram unit and the pump unit may be of the general utility type manufactured

by the Blackhawk Mfg. Co., Milwaukee, Wisconsin.

The pump unit 105 comprises a pump cylinder or reservoir 106 containing the fluid to be forced under pressure into the interior of the ram cylinder, and a rocking beam 107 adapted to be rocked about pivot 108 by means of an actuating lever 109 to produce reciprocation of a pressure plunger (not shown) within the head end of the pump unit thereby drawing fluid from the reservoir of the pump unit and transmitting it under pressure to the flexible conduit 102 through the outlet port fitting 104. The pump unit is provided at its end portions with suitable foot rest members 110 and 112 each presenting an upwardly disposed roughened surface upon which the operator can stand to maintain the pump unit in fixed position on the floor during reciprocation of the operating lever 109.

20 The portable ram unit, as shown in Fig. 2, is laid by the operator between the guide rods 61 and 62 of the rail structure 57 of the press 25 when a roll assembling operation is to be performed. When thus arranged, it will be apparent 25 that upon reciprocation of the actuating lever 109 of the pump unit 105, fluid under pressure will be forced through the flexible conduit 102 into the ram cylinder 100 thereby producing movement of the piston or plunger 101 axially 30 outwardly of the ram cylinder. Since the distal ends of the fluted portions 16 and 16' of the roll sections 10 and 12 respectively will be engaged by the sides of the clamps 59, 59' and 59'', which previously are clamped to the roll sections, this 35 axial outward movement of the piston 101 will be transmitted to the movable clamp 59'' and to the fixed transverse pressure plate 58 by the respective ends of the piston 101 and the ram cylinder 100 after engagement therewith. This results in the clamps 59'' and 59' having relative 40 movement towards each other when pressure is continued to be applied to the ram unit by further operation of the pump which results in shortening the distance between the clamp devices, and forcing the shank 14 of the roll section 10 completely 45 into the square bore of the tubular coupling sleeve 13 attached to the other roll section 12 whereby the outer cylindrical end portion 20 of the coupling 13 will be brought into engagement with the outer end of the short neck portion 17 of the roll section 10.

50 It will be evident from the above-described construction of the foregoing textile roll assembling and disassembling apparatus the union or the separation of the numerous roll sections which make up a lengthy drawing or feed roll thus becomes simple, thereby eliminating the slow and expensive hand work hitherto employed involving hammering operations to connect or driving-to-fit the parts together as has been previously required. In the operation of the textile machine, rolls assembled in this manner and by the apparatus of the present invention run with accuracy and perfect alignment throughout their entire length and there is no wobbling or unevenness in the rotation of the sections.

55 While there has been shown herein and described a preferred embodiment of the invention, it will be evident that the invention is not limited to the form herein shown nor to being applied to a spinning frame only which use was for illustrative purposes only, but it may be applicable in other forms and to other classes of textile machines such as roving frames and drawing frames, the scope of the invention being defined 60 in the claim appended hereto.

I claim:

Apparatus for use in joining or for separating a pair of fluted boss type textile drawing roll sections which are arranged for interfitting axial connection in end-to-end relation with each other, and for use in association with a small portable hydraulic ram unit having a cylinder with a movable plunger therein operated hydraulically by a pump unit, said apparatus comprising a frame including a pair of spaced elongated rod members, a cross bar and a stationary roll-clamping device each fixedly mounted on and extending between said rod members rigidly connecting the rod members in spaced parallel side-by-side relation providing a unitary rail structure, an intermediate movable roll-clamping device slidably mounted on and between said rod members for longitudinal adjustment bodily therealong between said cross bar and said stationary roll-clamping device, said stationary and movable roll-clamping devices each including in its structure cooperating fixed and movable jaw members adapted to clampingly grip the cylindrical neck part between adjoining fluted bosses of a textile drawing roll section to support a single roll section during joining or separation of the two roll sections, both of said clamping jaws of each clamping device being situated on the outside of the associated clamping device in extended relation beyond and at one and the same side of said rail structure and projecting therebeyond in a direction transversely of the path normally containing the axes of the respective roll sections to be joined or separated for supporting both roll

5

10

sections in axially aligned relation and in an outboard position with respect to said rail structure, said movable roll-clamping device being propelled by a ram unit to be positioned between and in engagement with said movable roll-clamping device and either said cross bar or said stationary roll-clamping device when a pump unit connected hydraulically with the ram unit is actuated to effect either union or separation of the roll sections carried by the respective roll-clamping devices.
